UNITED STATES PATENT OFFICE.

JOHN H. BAKER, OF DETROIT, MICHIGAN.

BOILER.

Application filed January 18, 1926. Serial No. 81,993.

My invention relates to a new and useful improvement in a boiler and is intended as an improvement over the boiler shown in my application, Serial No. 679,936 filed December 11, 1923. The present invention, besides embodying the advantages pointed out in said application, has as its object the provision of a boiler of this class provided with connected steam domes, each of which 10 communicates with a reservoir-forming portion, this reservoir-forming portion serving to compensate for the rising of the water from the bottom of the boiler, so as to prevent burning of the headers or containers at the 15 bottom of the boiler.

Another object of the invention is the provision of a boiler of this class, so arranged and constructed as to particularly accommodate itself for mounting in the restricted 20 space provided on a motor vehicle.

Another object of the invention is the provision of a boiler of this class having an intake pipe extending into one of the reservoirs and extending normally below the low water line in the reservoir, so that, upon delivery of water into the reservoir, a minimum disturbance is produced.

Another object of the invention is the provision of an oil skimming arrangement, 30 whereby the oil conducted to the reservoir by the incoming water may be skimmed off the water, utilizing the steam pressure in the boiler for this purpose, when desired.

Another object of the invention is the provision of a boiler of this class having a plurality of headers each connected with a plurality of tubes, the connected headers arranged in rows having the upper ends in closer proximity than the lower ends, so as 40 to provide a trap for retarding the flow of combustible gases, thus assuring a maximum absorption of heat by the water tubes of the boiler.

Another object of having the intake delivery pipe constructed as mentioned is to prevent the mixing of the incoming water with the steam contained in the upper portion of the reservoir and in the dome.

Another object of the invention is the provision of a structure so arranged as to assist the circulation of the water when moving because of convection.

Other objects will appear hereinafter.

The invention consists in the combination and arrangement of parts hereinafter described and claimed.

The invention will be best understood from a reference to the accompanying drawings, which form a part of this specification and in which,

Fig. 1 is a top plan view of the invention,

Fig. 2 is a side elevational view of the invention,

Fig. 3 is a front elevational view of the invention, taken on substantially line 3—3 65 of Fig. 2,

Fig. 4 is a sectional view taken on substantially line 4—4 of Fig. 2.

As shown in the drawings, the invention comprises a plurality of upper headers 9, 70 each embodying a tube closed at opposite ends. Each of these headers 9 is connected at one end by means of a U-shaped pipe 11 and a coupling 10 to a steam dome 12, 75 which is L-shaped to provide the depending reservoir-forming portion 13, the lower end 14 of which is reduced in diameter and connected to a tubular cross member 15, which communicates at its opposite ends with parallel extending pipes 16 and 17, which are closed at their opposite ends and extend at right angles to the cross member 15. The tubular member 16 is connected by means of the coupling 16' and the L-shaped pipe 16'' to one end of lower headers 18, the opposite 80 end of these headers 18 being connected by the L-shaped pipe 19 and the coupling 20 to the pipe 17. These lower headers 18 are connected to respective upper headers 9 by a plurality of tubes 21, each of which is 85 formed bow-shaped, as clearly seen in Fig. 2. As shown in Fig. 2, the headers 18 do not lie directly beneath the corresponding header 9, excepting in the case of the centrally positioned headers 9' and 18'. The outermost header 18, that is the header 18 lying closest to the reduced portion 14, is 90 spaced from the adjacent header a greater distance than is the corresponding header 9 spaced from its adjacent header, the location 100 of the headers at the opposite sides of the centrally disposed headers 9' and 18' being determined by proceeding outwardly from these centrally disposed headers. With a boiler constructed, according to this invention, for use on a conventional type of steamer automobile, the lower headers 18 would be spaced from each other approximately five-sixteenths of an inch, and the upper headers 9 would be spaced from each 105 other about two-sixteenths of an inch. The purpose of this arrangement is to provide

a trap for the combustible gases which proceed upwardly from the heating element which is positioned beneath the header 18. If desired the headers may be positioned 5 in vertical alignment and the upper headers made larger, and particularly where a large number of sections are used. This heating element may be of any desired or conventional type and forms no part of this invention, and therefore, is not shown.

As shown in Fig. 1, the dome 12, is connected by a pipe 22 to one of the legs 23 of a U-shaped dome, the steam outlet 24 being connected adjacent the other end. The purpose of such an arrangement is to force the steam generated in the boiler to travel the maximum distance in the domes, so that a dry steam may be utilized for power purposes. As shown in Fig. 3, the parallel extending tubular members 16 and 17 project beyond the cross member 15, to provide a portion upon which may be positioned a sleeve 25, which is welded to a supporting portion 26 of a Z-shaped bracket 27, the 25 other angularly turned end 28 of which engages the cross beam 29 of the chassis of the vehicle with which used. A similar sleeve 25' supported by a similar bracket 27' may be utilized for engaging the opposite ends of 30 the tubular members 16 and 17. It is, of course, apparent that where the boiler is used as a stationary boiler, this method of mounting may be varied to suit specific needs. An intake pipe or water delivery pipe 30 communicates with the interior of the steam dome 12 and is angularly turned to provide the downwardly extending pipe 31, which projects downwardly in the reservoir 13 below the normally low water line so that when 40 the water is taken into the boiler, it does not mix with the steam in the dome 12. Formed in the reservoir 13 is an opening 32 normally closed by a suitable plug and in which may be secured a suitable pipe for leading off the oil which may be carried into the reservoir 45 13 by the water delivered thereto. This oil will, of course, float upon the water and when the opening 32 is opened, while the boiler is under pressure, the oil will be blown 50 out of the opening 32 and through the pipe attached thereto.

As shown in Fig. 3, the leg 23 of the U-shaped dome is provided with an angularly turned depending reservoir forming portion 33, which is reduced at its lower end, to provide the tubular portion 34 which connects to the cross pipe 15. The depending reservoir portions 13 and 33, in addition to serving as storage tanks for the water used 55 in the boiler, also serves to assist the circulation of the water, particularly when the boiler is used on a vehicle, because of the pressure exerted downwardly by the water contained in the tubes 14 and 34 and by supplying a large volume of water for filling up

such vacancies as are caused by a sudden movement of the vehicle and the travel rearwardly of the water in the tubes 16 and 17, as well as the lateral travel of the water in the lower headers 18. These reservoirs also 70 serve to protect the headers from burning out because of the rising of the water from the headers, when the heat is rapidly applied, the large volume serving to supply additional water through the reduced portions 34 and 75 14, and the tubular members 15, 16 and 17. As shown in Fig. 3, a clean-out pipe 35 connects with the pipe 16. It is apparent that one of these clean-out pipes may be connected to the pipe 17, if desired. An additional steam outlet 36 may be used when necessary and projecting from the end of the dome 12 is a pipe 37 communicating with the balancing and indicating systems conventionally used on boilers. Positioned between the reservoirs 13 and 33 and the end layer of tubes 21 is a plate having opposite ends 38 and 39 angularly turned to the central portion 40, so as to permit the plate to lie between the reservoirs 13 and 33 and the 90 end layer of tubes 21. This plate serves as a shield to protect the reservoirs from the combustible gases so that proper circulation of the water will not be interfered with.

It will be noted that the structure of the 95 device is one which gives great flexibility to the boiler and provides advantages and features which render the boiler a durable one and especially adapted for use on motor vehicles. The arrangement of the tubes is 100 shown in Fig. 4 as being staggered relatively to each other, that is, the positioning of the tubes in one section is staggered in relation to the positioning of the tubes in the other section. This arrangement of the tubes and 105 the relative positioning of the headers, as already described, affords a boiler which may be utilized generally for the purposes of generating steam with a minimum amount of fuel.

While I have illustrated and described the 110 preferred form of structure, I do not wish to limit myself to the precise form of structure shown, but desire to avail myself of such variations and modifications as come 115 within the scope of the appended claims.

Having thus described my invention what I claim as new and desire to secure by Letters Patent is:

1. A boiler of the class described comprising an upper and lower set of headers, each set comprising a plurality of parallel extending headers in spaced relation to each other, the headers in the upper set being spaced apart a less distance than the headers 120 in the lower set; a plurality of bow shaped tubes connecting the corresponding headers in the upper and lower sets, the tubes connecting adjacent headers being in staggered 125 relation; an L-shaped dome having its base 120

- extending transversely of the upper set of said headers adjacent one end thereof; means for connecting said end of said headers in communication with the leg of said 5 dome; a U-shaped dome positioned transversely over the upper set of said headers adjacent the opposite end thereof, the leg of said U-shaped dome adjacent said L-shaped dome being angularly turned and extending 10 in parallel relation to the leg of said L-shaped dome; means for connecting the base of said L-shaped dome with said leg of said U-shaped dome; a reduced portion on the lower end of the leg of said 15 L-shaped dome; a reduced portion on the lower end of said angularly turned leg of said U-shaped dome; a transversely extending pipe in communication with said reduced portions; a pair of parallel extending 20 pipes, each in communication with said transversely extending pipe; and means for connecting said parallel extending pipes in communication with the headers of said lower set.
- 25 2. A boiler of the class described comprising an upper and lower set of headers, each set comprising a plurality of parallel extending headers in spaced relation to each other, the headers in the upper set being spaced apart a less distance than the headers in the lower set; a plurality of bow-shaped tubes connecting the corresponding 30 headers in the upper and lower sets, the tubes connecting adjacent headers being in staggered relation; an L-shaped dome having its base extending transversely of the upper set of said headers adjacent one end thereof; means for connecting said end of said headers in communication with the leg of said dome; a U-shaped dome positioned 35 transversely over the upper set of said headers adjacent the opposite end thereof, the leg of said U-shaped dome adjacent said L-shaped dome being angularly turned and extending in parallel relation to the leg of said L-shaped dome; means for connecting the base of said L-shaped dome with said leg of said U-shaped dome; a reduced portion on the lower end of the leg of said L-shaped dome; a reduced portion on the lower end of the lower set of said angularly turned leg of said U-shaped dome; a transversely extending pipe in communication with said reduced portions; a pair of parallel extending pipes, each in communication with said transversely extending pipe; means for connecting said parallel extending pipes in communication with the headers of said lower set; and a steam outlet pipe communicating 40 with the other leg of said U-shaped dome 45 adjacent its end.
- 50 In testimony whereof I have signed the foregoing.
- JOHN H. BAKER.
